Patented Dec. 30, 1958

184,203

CLIP FOR A PEN OR THE LIKE

Harold E. Zierhut, Granada Hills, Calif., assignor to Paper Mate Manufacturing Company, Culver City,
Calif., a corporation of Delaware

Application November 8, 1957, Serial No. 48,392

Term of patent 14 years

(Cl. D74—1)

Fig. 1.

Fig. 2.

Fig. 3.

Fig. 4.

Fig. 5.

Fig. 1 is a front view of a clip for a pen or the like showing my new design.

Fig. 2 is a side view thereof.

Fig. 3 is a top view of the clip shown in Fig. 2.

Fig. 4 is a bottom view of the clip shown in Fig. 2; and

Fig. 5 is a transverse section thereof taken on line 5—5 of Fig. 2.

I claim:

The ornamental design for a clip for a pen or the like, as shown.
